Peter John Corby, Braunstone, Leicester, England, assignor to J. & L. Randall Limited, Potters Bar, England, a company of Great Britain

Filed June 14, 1962, Ser. No. 70,551

Claims priority, application Great Britain Dec. 19, 1961

Term of patent 3½ years

(Cl. D34—5)

FIG. 3

FIG. 2

FIG. 1

FIG. 4

FIGURE 1 is a top and front perspective view of a three dimensional board for a game embodying my new design;

FIGURE 2 is a side elevational view thereof;

FIGURE 3 is a rear perspective view thereof; and

FIGURE 4 is an enlarged fragmentary elevational view thereof.

I claim:

The ornamental design for a three dimensional board for a game, as shown.
